CLAIM

The ornamental design for an arcuate display stand, as shown and described.

DESCRIPTION

FIG. 1 is a perspective view of the present invention;

FIG. 2 is a top plan view thereof;

FIG. 3 is a left side elevational view thereof;

FIG. 4 is a front elevational view thereof;

FIG. 5 is a right side elevational view thereof; and,

FIG. 6 is a back elevational view thereof.

The broken lines are for environmental purposes only and form no part of the claimed design.
